UNITED STATES PATENT OFFICE.

MICHAEL MINUTILLO, OF HOLYOKE, MASSACHUSETTS.

SHOE AND ARCH PRESERVER.

Application filed May 23, 1927. Serial No. 193,686.

This invention relates to shoes and more particularly to a supporter formed as part of the shoe and by means of which the shank portion of the shoe may be reinforced to retain the shoe in its proper shape.

One object of the invention is to form a portion of the brace integral with the inner sole of the shoe so that it will have smooth engagement with the shank and adjacent portions of the foot to brace the foot and prevent fallen arches and reinforce this brace forming portion of the inner sole so that it will be prevented from being forced out of shape after the shoe has been worn for some time.

Another object of the invention is to so form the reinforcement or auxiliary bracing means that it will fit smoothly in engagement with the brace forming portion of the inner sole and allow the shoe to have a neat appearance.

Another object of the invention is to so arrange the auxiliary bracing means for the shoe that the shoe will be braced transversely as well as longitudinally and thereby greatly strengthened at the shank portion.

The invention is illustrated in the accompanying drawing, wherein

Figure 1 is a view showing the improved shoe in side elevation, the upper or body portion of the shoe being indicated by dotted lines;

Fig. 2 is a transverse sectional view through the shoe taken on the line 2—2 of Fig. 1 with the upper omitted, and

Fig. 3 is a bottom plan view of the inner sole and associated bracing means.

The improvement constituting the subject-matter of this invention relates to the inner sole and, therefore, the upper or body portion of the shoe, which is indicated in general by the numeral 1, has been shown in dotted lines. The outer sole and heel are indicated by the numerals 2 and 3 and the inner sole by the numeral 4. The inner sole carries the usual welt strip 5 which is secured thereto in the usual manner and extends along the same, as shown in Fig. 3. The shank and adjacent heel and ball portions of the insole extend beyond the inner side of the outer sole and this extended portion of the insole is bent and curved upwardly so that it conforms to the contour of the instep of a foot and will have snug fitting engagement therewith when the shoe is worn. This portion of the insole will, therefore, constitute an instep bracing portion which is indicated by the numeral 6 and since it is formed of leather and is integral with the insole it will be comfortable to wear and overcome a tendency which some people have to turn the shoe inwardly when walking. In order to reinforce the brace forming portion of the insole, there has been provided a bracing sheet 7 which may be referred to as an auxiliary brace and is cemented or otherwise secured to the under face of the inner sole. This bracing sheet underlies the inner sole, as shown in Fig. 3, and is curved longitudinally and transversely so that it has smooth fitting engagement therewith and conforms to the contour of the portion of the insole against which it fits. This bracing sheet is also formed of leather and will serve to greatly strengthen the brace forming portion of the insole. It should also be noted that a portion of the welt strip 5 extends longitudinally under the bracing sheet and is secured thereto in any desired manner. The auxiliary bracing sheet also overlaps the metal reinforcing strip 8 which extends longitudinally upon the instep portion of the insole and has one end secured to the heel portion thereof by a fastener 9 and its forward end portion secured against the ball portion of the insole and covered by a pad 10 which may be formed of paper or any other suitable material. It is desired to provide additional bracing means for the instep portion of the shoe and in order to do so I employ strips 11 which extend transversely across the insole between its under face and the bracing sheet. These strips extend across the shank portion of the insole, as shown in Fig. 3, and have their outer end portions projecting upwardly from the marginal edge of the brace forming portion of the insole, as shown in Figs. 1 and 2. It will thus be seen that the instep portion of the shoe will be very firmly braced both longitudinally and transversely and will not be liable to be forced out of shape when the shoe is worn. The strips 11 may be formed of heavy cardboard, leather, sheet metal or any other desired material having sufficient strength to reinforce the brace forming portion of the insole without causing the shoe to be uncomfortable by pressure being exerted against the instep portion of the foot.

Having thus described the invention, I claim:

1. A shoe comprising a main sole, an inner

sole having its inner side portion extended transversely from the main sole along the instep and adjacent heel and ball portions thereof and curved upwardly to form a brace 5 for the instep portion of the shoe, an auxiliary bracing sheet of stiff material for the instep portion of the inner sole and brace forming portion thereof fitting against the under face thereof with its outer side face 10 spaced from the adjacent side edge of the inner sole, and bracing strips extending transversely between the bracing sheet and instep portion of said inner sole with their outer end portions projecting from the bracing sheet and extending beyond the marginal edge of the brace forming portion of the inner sole.

2. A shoe comprising a main sole, an inner

sole having its inner side portion extended transversely along the instep and adjacent 20 heel and ball portions and curved upwardly to form a brace for the instep portion of the shoe, an auxiliary bracing sheet having a portion disposed beneath the instep portion of the inner sole and a portion curved 25 upwardly against the outer face of the brace forming portion of the inner sole, and a metal reinforcing strip extending longitudinally beneath the instep portion of the inner sole and secured thereto and throughout the 30 major portion of its length overlapping said bracing sheet.

In testimony whereof I affix my signature.

MICHAEL MINUTILLO. [L. s.]
